UNITED STATES PATENT OFFICE.

PHILIP DIEHL, DECEASED, LATE OF ELIZABETH, NEW JERSEY, BY RUDOLPH DIEHL, OF BROOKLYN, NEW YORK, AND MAX H. KEPPLER, OF ELIZABETH, NEW JERSEY, EXECUTORS, AND MARTIN HEMLEB, OF ELIZABETH, NEW JERSEY, ASSIGNORS TO THE SINGER MANUFACTURING COMPANY, A CORPORATION OF NEW JERSEY.

SEWING-MACHINE LOOP-TAKER.

1,179,371.

Specification of Letters Patent. Patented Apr. 11, 1916.

Application filed June 12, 1913. Serial No. 773,187.

To all whom it may concern:

Be it known that PHILIP DIEHL, late a citizen of the United States residing at Elizabeth, in the county of Union and State of New Jersey, and MARTIN HEMLEB, a citizen of the United States, residing at Elizabeth, in the county and State aforesaid, did invent certain new and useful Improvements in Sewing-Machine Loop-Takers, of which the following is a specification, reference being had therein to the accompanying drawings.

This invention has for its object to provide a loop-taker of that type in which the thread-case is journaled within the loop-seizing member and is either wholly or partially removable therefrom for renewal of the mass of lower thread or for threading and adjustment of the lower thread tension.

Owing to the described relation of the relatively movable parts, it is important that the thread-case should be made as light as possible; and to this end, in a preferred embodiment of the present improvement the thread-case is constructed to omit the usual axial bobbin supporting pin and the central portion of the bottom of the thread-case which sustains the same. In thread-cases composed of separable sections locked together by means of latch devices such as that of the pending application of P. Diehl and M. Hemleb Serial No. 662,595, it has been customary to provide the body section not only with a bottom member sustaining an axial journal-pin, but to provide the cap member with a tubular bobbin-supporting post fitted to the journal-pin; but according to the present construction such pin and post are dispensed with, thereby materially lightening the bobbin-case.

Another desideratum of a thread-case is to secure a substantially direct lead of the lower thread from beneath the tension spring to the work without passing around any abrupt corners. According to the present improvement, the thread is led through the lower side wall of the thread-case and across the outer face almost diametrically

beneath a flat tension spring, thence through a delivery eye near the upper periphery of 50 the outer face of the case and through a guide-channel in the holding lug in practice engaged by a stationary member of the machine for restraining the thread-case against turning, the thread being led from such 55 channel directly to the work. By this means, a uniform tension of the thread is assured and untwisting and kinking are prevented.

The invention will be understood by reference to the accompanying drawings, in which—

Figure 1 is an outer face view of a loop-taker embodying the present improvements, and Fig. 2 an edge view of the same with 65 the loop-seizing member in section. Fig. 3 is a transverse sectional view of the thread-case. Fig. 4 is a perspective view of the body section, Fig. 5 an inner face view of the cap section, and Fig. 6 a perspective 70 view of the cap section with the tension spring and latch member omitted. Fig. 7 is a perspective view of the tension spring, Fig. 8 a similar view of a plate formed with the thread-delivery aperture, and Fig. 9 is 75 a perspective view of the latch member.

The loop-seizing or hook-member is shown formed of a ring 1 connected by radial arms 2 with the hub 3 adapted to be secured upon a rotary actuating shaft. As described in 80 our said application, the member 1 is cut away upon one side of its periphery and provided with the beak 4 and loop-deflector 5. This member is cup-shaped to afford an axial thread-cavity 6 in whose side wall is 85 formed an annular groove 7.

As herein represented, the sectional thread-case is composed of the cylindrical body section 8 provided with the segmental rib or flange 9 fitted within the groove 7 of 90 the hook member, and the cap section which is formed with the cylindrical side-wall 10 and outer end wall 11. The cylindrical side-wall of the cap section is fitted within that of the body section 8 with its extremity 95 resting against an annular shoulder pro-

vided therefor. The cap and body sections together inclose a cylindrical space which is uninterrupted between its ends both axially and diametrically to afford a thread-cavity 5 to receive the lower thread bobbin 12; and the body section is formed as a cylindrical shell open at both ends and having at its inner end, or that opposite the closed end of the cap section, the narrow inturned flange 10 13 serving to confine the adjacent flange of the bobbin 12 in position.

The body section 8 is provided in the upper portion of its periphery with the outwardly and upwardly projecting holding lug 14 having the radial channel 15 adapted to be entered by a fixed holding element sustained by the machine frame. In one side of its periphery, this body section is formed with a slot 16 terminating at the outer end 20 in a notch 17 in a lateral flange or projection 18. The flange 9 is interrupted at one side of the section 8 to afford the usual loop-containing shoulder 19 against which the needle-thread loop is carried by the hook 4 in 25 casting the same about the lower thread.

The wall 10 of the cap section is provided in one side with the threading slit 20 extending from the inner edge and terminating intermediate the edges in the aperture 30 21. The outer end of the cap section is shown provided with a lateral rib 22 formed with a thread-guiding notch 23 in substantial alinement with the slit 20 and connected therewith by means of the groove 24.

35 At the opposite side from the notch 23 of the end disk 11 of the cap section and nearly diametrically opposite, is the flat plate 25 secured in position by rivets 26 and formed with an inclined slot 27 terminating in the thread-delivery aperture 28, thereby producing a laterally extending tongue 29. As represented in the drawings, the outer face of the tongue 29 is substantially flush with that of the end disk 11, 40 and the extremity of this tongue is outwardly inclined at 29', as represented in Figs. 6 and 8 to freely admit the lower thread beneath the same in threading. A transverse channel 30 is formed in the outer 45 face of the member 11 intermediate the notch 23 and thread-delivery aperture 28 in which is secured by means of the screw 31 the flat tension spring 32, the bottom of the channel affording a countersunk seat 50 disposed below the outer face of the plate 25.

As shown in Fig. 6, the lower thread *a* leading from the bobbin passes through the thread aperture 21 and thence through the groove 24 and notch 23 along the bottom 60 of the channel 30 and beneath the plate 25 to the delivery aperture 28 from which it emerges in its passage to the under side of the work. As represented in Fig. 1, the cap

section is so disposed relatively to the bottom section of the thread-case that the notch 65 23 and delivery aperture 28 are in substantial alinement with the channel 15 of the holding lug 14 through which the thread is adapted to be led in a nearly direct line from the tension spring through the usual needle 70 aperture in the throat-plate to the work. To insure this relation of the separable bobbin-case sections, the rib 22 is cut away on one side to afford shoulders 22' which engage the opposite edges of the holding lug 75 14 as represented in Figs. 1 and 5.

In order to detachably secure the cap section to the body section, a latch device is employed which is similar to that of the United States patent to W. Brandt No. 80 537,547, of April 7, 1896. The member 11 is shown formed with the undercut spaced parallel ribs 33 and 34 disposed transversely to the tension spring 32, the rib 34 being formed with a socket 35 to receive the spring 85 36 (shown in dotted lines in Figs. 1 and 2). Fitted to these ribs along the opposite edges is the sliding latch-plate 37 provided with the lateral lug 38 to receive the thrust of the spring 36, and with the inturned finger 90 39 having the wedge-shaped extremity 40 and the latch shoulder 41 adapted to enter the slot 16 of the body section and to engage the projection 18, as represented particularly in Figs. 2 and 3. A clearance aperture 42 is formed in the side wall and end member 11 of the cap section to accommodate the slide-plate and its finger 39.

At the end opposite the finger 39 the latch-plate 37 is forked and provided with 100 bosses 43 to receive the pin 44 which affords a pivotal connection of the latch-plate with the tongue 45 attached to the finger-piece 46. The member 11 is formed with the aperture 47 to admit the tongue 45 which latter, when the finger-piece 46 is raised, acts upon the cross-bar 48 intermediate the apertures 42 and 47 of the member 11 to force the latch-plate 37 backwardly so as to disengage the finger 39 from the projection 18 of the 110 thread-case section 8. The head of a stop-screw 49 upon the inner face of the latch-plate 37 engages the cross-bar 48 to limit the retractive movement of the latch so as to hold the finger-piece 46 rigid for use as 115 a handle in withdrawing the cap section for renewing the bobbin or for other purposes.

In applying a bobbin to the cap section, as herein represented, the bobbin is introduced and the thread drawn through the 120 threading slit 20 into the aperture 21, after which it is led through the notch 23 between the adjacent edges of the spring 32 and channel 30, and thence forwardly beyond the extremity of the tongue 29 and laterally 125 toward the delivery aperture 28. In this

lateral movement, the thread is directed by an upturned lip 32' of the spring adjacent to the tongue 29 downwardly so as to lead from the bottom of the channel beneath the inclined point of the tongue 29, under which it is drawn into the delivery aperture. In the casting of the needle-thread loop about the thread-case in the production of the first stitch of a series, the lower thread is drawn upwardly to the under side of the work, being thus caused to pass through the channel 15 of the holding lug 14 so as to assume nearly a direct lead from the tension spring 32 to the work and thereby avoid the tendency to untwisting and kinking to which it has been subjected in loop-takers of other construction.

While the present improvement is herein shown and described in what is considered its preferred form, it is obvious that it may be readily adapted to other types of loop-taker than that of the present embodiment and that it is susceptible of material modification in constructive features without departure from the scope of the invention.

Having thus set forth the nature of the invention, what is claimed herein is:—

1. A sewing machine loop-taker comprising a loop-seizing member and a sectional thread-case including a body section journaled within the loop-seizing member and open centrally at both ends, a cap section applied to and adapted to close one end of the body section to which it is detachably secured, and an inturned bobbin-confining flange provided upon the end of said body-section opposite the cap section.

2. A sewing machine loop-taker comprising a loop-seizing member formed with a cylindrical thread-cavity provided with an annular raceway in its inner side-wall, and a sectional thread-case including an open-ended body-section having a peripheral bearing rib entering said raceway and providing a thread-cavity uninterrupted between its ends both axially and diametrically and a cap-section applied to one end of the body-section and provided with peripherally disposed means for positively and detachably locking it to the body-section, said thread-case being constructed to confine a bobbin therein independently of the loop-seizing member.

3. A sewing machine loop-taker comprising a loop-seizing member and a thread-case journaled therein and formed with a thread-cavity and closed at its outer end which sustains a flat tension spring disposed substantially diametrically thereof, a latch element transverse to said spring whereby the thread is locked within the thread-cavity, and substantially diametrically opposite thread-guides at the periphery of said outer

end of the thread-case whereby the thread is guided in a straight line and under said tension-spring.

4. A sewing machine loop-taker comprising a loop-seizing member and a cylindrical thread-case journaled therein and formed with a closed outer end provided with a laterally extending tongue beneath which the thread is delivered and opposite peripherally disposed thread-guides and a channel intermediate said thread-guides and directed toward and transversely of said tongue, and a tension spring secured within said channel and adapted to produce a drag upon the thread leading beneath said tongue.

5. A sewing machine loop-taker comprising a loop-seizing member and a cylindrical thread-case journaled therein and formed with a closed outer end provided with a laterally extending tongue beneath which the thread is delivered and opposite peripherally disposed thread-guides and a transverse seat intermediate said thread-guides and directed toward and arranged below the outer face of said tongue, and a tension spring secured upon said seat and adapted to produce a drag upon the thread leading beneath said tongue.

6. A sewing machine loop-taker comprising a loop-seizing member and a cylindrical thread-case journaled therein and formed with a closed outer end provided with opposite peripherally disposed thread-guides, a laterally extending tongue having an outwardly inclined extremity from beneath which the thread is delivered, a transverse seat intermediate said thread-guides and directed toward and arranged below the outer face of said tongue, and a tension spring secured upon said seat and provided upon the edge adjacent the extremity of said tongue with an upturned lip for directing the thread led beneath the same under the extremity of said tongue.

7. A sewing machine loop-taker comprising a loop-seizing member and a cylindrical thread-case journaled therein and formed with a closed outer end provided near the periphery with a thread-delivery aperture and at the opposite side with a thread-slit extending through the side wall and a thread-guiding notch in the periphery of the end in substantial alignment with said thread-slit, and a tension spring secured to the end of the thread-case intermediate the thread-delivery aperture and thread-guiding notch and adapted to produce a drag upon the thread leading from the interior of the thread-case and across the outer end thereof.

8. A sewing machine loop-taker comprising a loop-seizing member and a cylindrical thread-case journaled therein and provided at one side of its outer end with a lateral

holding lug formed with a thread channel and with a thread-delivery aperture near the periphery and in substantial alinement with said channel and having at the periphery 5 of the opposite side a thread-guiding notch in alinement with said channel and delivery aperture, a threading slit being formed in the side wall of the thread-case extending toward said thread-guiding notch, and a tension spring secured to the end of the thread-case intermediate the thread-delivery aperture and thread-guiding notch and adapted 10 to produce a drag upon the thread leading from the interior of the thread-case and 15 across the outer end thereof.

In testimony whereof, we have signed our names to this specification, in the presence of subscribing witnesses.
